DESIGN FOR A HAT

Paul M. Maxwell, Manhasset, and Esther Lundberg, New York, N. Y., assignors to Hat Corporation of America, Norwalk, Conn., a corporation of Delaware

Application July 14, 1941, Serial No. 102,123

Term of patent 3½ years

To all whom it may concern:

Be it known that we, Paul M. Maxwell and Esther Lundberg, citizens of the United States, residing, respectively, at Manhasset, county of Nassau, and State of New York, and at New York, county of New York, and State of New York, have invented a new, original, and ornamental Design for a Hat, of which the following is a specification, reference being had to the accompanying drawing, forming a part thereof, and in which:

Fig. 2 is a rear view of the hat shown in Fig. 1.

We claim:

The ornamental design for a hat, as shown.

PAUL M. MAXWELL.

ESTHER LUNDBERG.
